(57) CLAIM

The ornamental design for a “cleaning implement,” as shown and described.

DESCRIPTION

FIG. 1 is a front perspective view showing one embodiment of a “cleaning implement” incorporating the design of my invention;

FIG. 2 is a top view thereof;

FIG. 3 is a bottom view thereof;

FIG. 4 is a side view thereof;

FIG. 5 is another side view thereof;

FIG. 6 is a front view thereof;

FIG. 7 is a rear view thereof;

FIG. 8 is a front perspective view showing another embodiment of a “cleaning implement” incorporating the design of my invention;

FIG. 9 is a top view of the cleaning implement shown in FIG. 8;

FIG. 10 is a bottom view of the cleaning implement shown in FIG. 8;

FIG. 11 is a side view of the cleaning implement shown in FIG. 8;

FIG. 12 is another side view of the cleaning implement shown in FIG. 8;

FIG. 13 is a front view of the cleaning implement shown in FIG. 8; and,

FIG. 14 is a rear view of the cleaning implement shown in FIG. 8.

The broken lines in FIGS. 1 to 14 showing bristles are for illustrative purposes only and form no part of the claimed design. The dotted area in FIGS. 8 to 14 illustrates different pattern or ornament used in that part of the design of the invention.
